CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The unshaded broken line circle and unshaded broken line ridges within the shaded area form no part of the claimed design. The broken line immediately adjacent to the internal perimeter of the solid line represents the bounds of the claimed design and forms no part thereof. The broken lines immediately adjacent to the shaded areas define the bounds of the claimed design and form no part thereof. The broken lines depicting the remainder of the shoe form no part of the claimed design.
